Patented May 28, 1912.

UNITED STATES PATENT OFFICE.

GEORGE LESSIG, OF READING, PENNSYLVANIA.

RAILWAY-TIE.

1,027,661.

Specification of Letters Patent. Patented May 28, 1912.

Application filed October 3, 1911. Serial No. 652,611.

To all whom it may concern:

Be it known that I, GEORGE LESSIG, citizen of the United States, residing at Reading, in the county of Berks and State of Pennsylvania, have invented certain new and useful Improvements in Railway-Ties, of which the following is a specification.

This invention relates to improvements in railway ties, more particularly to the class 10 of metal railway ties, and has for one of its objects to provide a simply constructed tie which is strong and durable and sufficiently yieldable to prevent damage to the rolling stock when passing over the tracks which 15 are supported upon the improved tie.

Another object of the invention is to provide a tie built up of a plurality of plates which not only provide the necessary "spring" or yieldableness, but likewise enable the broken or impaired portions to be 20 renewed without necessity for discarding the whole tie.

With these and other objects in view, the invention consists in certain novel features 25 of construction as hereinafter shown and described, and then specifically pointed out in the claims, and in the drawings illustrative of the preferred embodiment of the invention; Figure 1 is a side elevation partly in 30 section, of the improved tie with the rails in position thereon; Fig. 2 is a plan view of a portion of the improved tie; Fig. 3 is a section on the line 3—3 of Fig. 1 looking in the direction of the arrow.

35 Corresponding and like parts are referred to in the following description and indicated in all the views of the accompanying drawings by the same reference characters.

The body of the improved tie is built up 40 from a plurality of metal plates represented at 10, and the usual length and width of a tie and with a sufficient number of the plates employed to equal when combined the total 45 thickness of the tie. The ordinary tie is about eight feet long, eight inches wide, and ten inches thick, and these dimensions will 50 preferably be followed, but may be varied as circumstances may require. The plates 10 may be of any suitable thickness, and may be increased or decreased to correspond to the strain to which they will be subjected by the rolling stock. When employed upon heavy freight tracks, the plates will be heavier than 55 when employed for ordinary passenger traf-

fic. The plates will preferably be of steel 55 and preferably about two or two and a half inches thick.

Mounted upon the body 10 at the ends are "jackets" or rail supports which are formed with an upper side 11 bearing upon the 60 upper plate 10 and with downwardly directed flanges 12 at the sides which bear over the side edges of two or more of the plates and with a downwardly directed terminal flange 13 which bears over the ends of two 65 or more of the plates. The plates 10 are perforated near the ends and the upper members 11 of the rail supports are likewise perforated to register with the perforations of the plates, the perforations designed to 70 receive a relatively heavy clamp bolt 14 which is formed with a head 15 at the lower end and a nut 16 at the upper end. By this means the jacket or rail support is firmly 75 secured to the body.

Each of the rail supports is provided with a transverse rail-receiving recess 17 and with apertures 18 adjacent to the recess to receive clamp bolts 19 for engaging the tie flanges of the rails, the latter being represented conventionally at 20. Any number of the clamp bolts may be employed, but generally two, one at each side of the rail will be used, as shown. By this simple means the rail is firmly clamped to the rail support or jacket, 85 and the latter likewise firmly secured to the tie body.

The improved tie is simple in construction, can be inexpensively manufactured, is very durable and practically indestructible, while 90 at the same time the body portion being constructed of a plurality of plates 10, will yield to the rolling stock as it passes over the rails, and thus obviate injury from the "pounding" or impact of the wheels. 95

Having thus described the invention, what is claimed as new is:

1. A railway tie comprising a body formed of a plurality of superimposed metal plates, rail supports bearing upon the body at the 100 ends and provided with downwardly depending flanges engaging over the side edges and ends of a plurality of the plates, and means for connecting the body members together and likewise for connecting the rail supports 105 to the body members.

2. A railway tie comprising a body formed of a plurality of superimposed metal plates,

5 rail supports bearing upon the body at the ends and provided with downwardly depending flanges engaging over the side edges and ends of a plurality of the plates, said rail supports each having a transverse recess for receiving the tie flange of a rail, clamp bolts engaging in said rail supports and provided with heads adapted to extend over the flange of a rail, and clamping means operating

through said rail supports and body members.

In testimony whereof I affix my signature in presence of two witnesses.

GEORGE LESSIG. [L. S.]

Witnesses:

JAIRUS LESSIG,
WILLIAM LESSIG.
